UNITED STATES PATENT OFFICE

2,558,877

PRINTING PLATE AND METHOD OF
MANUFACTURINGThomas I. Ress, Chicago, Ill., assignor to The
Pioneer Electric and Research Corp., Forest
Park, Ill., a corporation of Illinois

Application January 25, 1949, Serial No. 72,623

4 Claims. (Cl. 101—401.1)

1

This invention relates to thin plastic printing plates and a method of making such plates, and it is an object of the invention to provide an improved printing plate and an improved method of manufacturing.

To facilitate the handling of charge accounts, department stores and other places of business have made up individual charge plates or printing plates of metal for each customer. When such customer makes a purchase, he presents his charge plate which identifies him and makes it unnecessary for the clerk to call a central department to determine if the purchaser has a charge account. Furthermore, the printing or charge plate is placed in a printer along with the sales slip and an imprint is made thereon of the information on the plate which usually includes a customer's name, address, and account number.

Such prior plates, while small, include rims for stiffening purposes so that they are relatively bulky, and it is not desirable to place them in men's billfolds, for example. Consequently, men usually carry them loose in coat pockets with the attendant possibility of loss or inconvenience in having to look for them. Carrying such plates in billfolds may result in their becoming bent or distorted so that they are not usable in the printing machine. Accordingly, it is a further object of the invention to provide a printing plate which is flexible and occupies small space.

It is a further object of the invention to provide an improved printing plate of the character described which is economical to manufacture.

It is a further object of the invention to provide an improved plate of the character indicated having clear and sharply defined characters thereon.

It is a further object of the invention to provide an improved method for forming printing plates of the character described having clear and sharp characters thereon.

In carrying out the invention in one form, a pair of flat, metallic members are assembled one on top of the other, which assembly is then passed between a pair of rolls having corresponding male and female characters arranged thereon. Thereafter the metallic members are reversed in relative positions, a thermoplastic blank is placed therebetween, and heat and pressure are applied thereto for causing the thermoplastic material to flow into the spaces defined by the characters. This method forms a plastic printing plate comprising a substantially flat, flexible plastic member having characters projecting upwardly therefrom on one side.

For a more complete understanding of the in-

vention, reference should be had to the accompanying drawings in which:

Figure 1 is a perspective view of a printing plate embodying the invention;

Fig. 2 is a perspective view diagrammatically indicating apparatus for making printing plate dies;

Fig. 3 is a sectional view of the rolls for forming the dies with the completed dies therebetween, the various parts being separated for clarity;

Fig. 4 is a perspective view of the top surface of one die;

Fig. 5 is a perspective view of the bottom surface of the other die;

Fig. 6 is a perspective view of the dies and material to be formed in relative positions;

Fig. 7 is a side view, partially in section, of a fixture for holding the assembled dies and material to be formed;

Fig. 8 is a view, partially in perspective, of the fixture of Fig. 7 in open position, and

Fig. 9 is an elevational view of heating and pressure apparatus with the fixture of Fig. 7 therein and in section.

Referring to Fig. 1 of the drawings, a printing plate 10 formed by the method of the invention is shown.

Printing plate 10 comprises a flat piece of thermoplastic material having any desired dimensions upon which a suitable series of characters 11 have been formed, the characters, for example, giving the name, street address, city, and account number of any particular individual. It will be understood that such information is only by way of example, and any other information may be embodied in the characters. The plate 10 may be made relatively thin so that it is flexible and occupies relatively little space. However, it may have sufficient resilience so that even though it is deformed it will spring back to its normal flat character.

The plate may be made of any suitable thermoplastic material, such for example as cellulose acetate in any color.

If desired, suitable notches 12 may be placed around the periphery of the plate in order that it may be properly oriented in a printing apparatus.

The characters 11 are sharply defined letters at the top of raised portions 20. Accordingly, the letters are not prevented by the surrounding material from making a sharp imprint on sales slips, for example.

In the remaining figures, the process of forming the plastic printing plate is shown. Referring

to Figs. 2 and 3, there is shown a pair of rolls 13 and 14 held in operative relationship relative to each other by shafts and bearings, not shown. Roll 13 has indentations 23 formed inwardly from its outer surface with letters 15 corresponding to the series of characters 11 on the printing plate at the top of the indentations. The indentations correspond to the raised portions 20. Likewise, roll 14 has raised portions 22 formed thereon outwardly from its surface with letters 16, also corresponding to the series of characters 11 on the printing plate at the top of the raised portions. Letters 15 and 16, respectively, together with corresponding indented and raised portions, are female and male parts of rolls 13 and 14 for suitably forming dies.

A pair of thin metallic blanks 17 and 18 of the same general shape as plate 10 are superimposed on each other, as may be visualized from Fig. 2. The superimposed blanks 17 and 18 are passed through rolls 13 and 14 whereby each of the blanks are formed therein a series of characters corresponding to the characters on the rolls. The blanks, after having been passed through the rolls, may be designated as dies or templates 19 and 21 corresponding respectively to blanks 17 and 18.

The raised and indented parts 22 and 23 of rolls 13 and 14 are of such size relative to each other that blanks 17 and 18 may be passed therebetween and the raised parts 22 will force the metal of the blanks into the indented parts 23, as may be visualized from Fig. 3. Letters 15 being formed inwardly with indented parts 23, when blanks are passed between the rolls the upper blank 17 is formed into die 19 with sharp letters 15a on top because of the direct contact of the blank with letters 15 of roll 13. Likewise, the letters 16 being formed outwardly of raised parts 22, the bottom blank 18 is formed into die 21 with sharp letters 16a on the underside thereof due to the direct contact of the blank with letters 16 of roll 14. Because the metal of blank 18 is pushed into the metal of blank 17, the abutting surfaces of the characters on the blanks as originally disposed are not so sharp as the letters on the top of die 19 and the letters on the bottom of die 21.

In Fig. 4 there is shown the die 19 with the top surface uppermost and showing the sharp letters 15a on top of raised portions 19a. Only sufficient letters to show the formation are shown in perspective in this view. In Fig. 5 there is shown the die 21 with the bottom surface uppermost showing indented portions 21a with the letters 16a sharply imprinted therein.

In Fig. 6 there is shown the arrangement of dies 19 and 21 and a thermoplastic blank 22 interposed therebetween. It will be noted that in this arrangement die 19 is below die member 21. That is to say, die member 19 formed as a female die (Fig. 3) now becomes a male die. In this manner, when heat and pressure are applied to the assembled dies and thermoplastic blank, the material of the blank is forced into the female portions of die 21 by the male portions of die 19. The material of the thermoplastic blank is forced into contact with the sharp characters on the underside of die 21 by the sharp characters on the top surface of die 19.

In the process of forming dies 19 and 21, the underside of the indentations in die 21 are somewhat smaller than the outside of the raised portions of die 19 inasmuch as these are forced one into the other. Therefore, when their posi-

tion is reversed, as in Fig. 6, and heat and pressure applied, the metal surfaces of the raised and indented portions fit closer to each other and therefore push the thermoplastic material into sharper formations. That is to say, there is a greater tendency for the metal to flow into every small crevice or space which exists. In this fashion, not only do the letters have sharp outlines, but their top surfaces which do the actual printing are sharp and even.

In Figs. 7, 8 and 9, a jig 25 for holding the dies and blank, and the apparatus 43 for applying pressure and heat thereto are shown.

Jig 25 includes an insulating handle 26 to which a base member 27 is attached by any well known means such as a bolt 28. Around the outside edge of base 27 there is a rim 29 forming a rectangular area 31 therein which is of sufficient size to receive dies 19 and 21 as well as thermoplastic blank 22. The die 19 is first placed in area 31 with blank 22 on top thereof, after which die 21 is placed on top of the blank. Overlying the top of die 21 is a member 32 having an indented or cut-out portion 33 corresponding to the area of the characters on die 21. Member 32 is held to a suitable backing member 34, which in turn is attached to a strap 35 extending the full length. Studs 36 and 37 are arranged at the ends in order to align the fixture parts always in the same relative positions and a threaded stud 38 and nut 39 are arranged as shown to hold the parts assembled.

In Fig. 8 the parts of the fixture are shown as though the upper part, i. e. strap member 35, were pivoted around its forward end so as to have it lying out flat, and the dies and blanks are shown separated and in perspective in their proper relative positions. Thus the operating surfaces of all parts of the fixture are viewable. Blank 22 is shown formed into a printing plate.

When the dies and blanks are assembled into the fixture as shown, the space 33 receives the letters on top of the die 21 so that no direct pressure is exerted tending to flatten the letters. After the assembly has been made, the fixture is inserted between the members 41 and 42 of the press 43, which for example may be a hydraulic press. Members 41 and 42 may be heated in any suitable fashion, and as shown, an electric cord 44 is connected thereto for supplying heating current to the members 41 and 42. A cord 45 is provided for connecting the heater in member 41 with the heater in member 42. The fixture is left in the press for a suitable length of time to plasticize the thermoplastic material and to allow the pressure exerted to force the material to flow into the spaces provided by the die members.

Depending upon the type of material used, different pressures and temperatures may of course be used, as is well understood by those skilled in this art.

While particular embodiments of the invention have been shown, it will be understood, of course, that the invention is not limited thereto since many modifications may be made, and it is, therefore, contemplated by the appended claims to cover any such modifications as fall within the true spirit and scope of the invention.

The invention having thus been described, what is claimed and desired to be secured by Letters Patent is:

comprising the steps of, forming a male die and a female die by placing a pair of thin metallic members together and applying pressure thereto with die members having male and female characters, reversing the relative position of said male die and said female die, placing a thermoplastic sheet between said reversed dies, and applying heat and pressure to the assembly.

2. The method of forming a flat plastic article comprising the steps of, assembling a pair of flat metallic members one on top of the other, imprinting said pair of members with a male and female character arrangement, reversing the position of said members after imprinting, placing a thermoplastic sheet between said reversed members, and applying heat and pressure thereto.

3. The method of forming a flat plastic article comprising the steps of, assembling a pair of flat metallic members one on top of the other, passing said assembled members between a pair of rolls having a male and female character arrangement thereon, reversing the position of said members after rolling, placing a thermoplastic sheet between said reversed members, and applying heat and pressure thereto.

4. The method of forming a flat plastic article comprising the steps of, assembling a pair of flat metallic members one on top of the other, imprinting said pair of members with a male and female character arrangement, reversing the position of said members after imprinting, placing a sheet of thermoplastic material between said reversed members, applying heat and pressure thereto, and cooling and separating said reversed members.
